SANITARY DRINKING FOUNT

Filed March 23, 1928

Inventor
Louis C. Rathbun.

By G. C. Kennedy.

Attorney

UNITED STATES PATENT OFFICE.

LOUIS C. RATHBUN, OF OELWEIN, IOWA.

SANITARY DRINKING FOUNT.

Application filed March 23, 1928. Serial No. 264,134.

My invention relates to improvements in drinking fountains, and the object of my improvement is to supply a fountain device adapted to be movably associated with a 5 faucet to be placed in communication therewith or to be shifted out of communication therewith when not in use, said device being automatically resiliently controlled to normally remain out of communication with 10 the faucet until manually brought into communication therewith releasably, and said device including means for closing both open ends of the fountain for sanitary purposes when the fountain is not in communication 15 with the faucet.

This object I have accomplished by the means which are hereinafter described and claimed, and which are illustrated in the accompanying drawings, in which Fig. 1 is 20 a front elevation of my improved drinking fountain mounted upon a faucet but shifted out of communication therewith and having both of its open ends closed by the closure means therefor, parts of the fountain device 25 being shown in vertical longitudinal section. Fig. 2 is a side elevation of the devices of said Fig. 1, but showing the drinking fountain in operative communication with said faucet. Fig. 3 is an under plan view of the 30 drinking fountain and its clamping means for the faucet, the fountain being in relative position shown in said Fig. 1.

My invention is not restricted to the precise construction and arrangement of parts 35 herein shown and described, nor to the various details thereof, as the same may be modified or rearranged in various particulars without departing from the spirit and scope of my invention, one practical embodiment of which has been herein illustrated and described without attempting to show all of the various forms and modifications in which my invention might be embodied.

The numeral 1 denotes a faucet of a well 45 known type having an operating crank handle 2 on the stem of a rock valve therein and having the usual downwardly curved spout 3.

My drinking fountain device includes a 50 clamping sleeve 4 embracing the termination of said spout and secured removably thereon by means of set-screws, or their equivalent, at 5. At one side said sleeve 4 has a depending stop projection 20, and opposite said projection has an angularly di-

rected substantially horizontal shelf 6, provided with the annular hole 24 which, however, is merely the open lower end of the sleeve 4. A laterally directed horizontal 60 arm 7 has one end downturned and rigidly mounted upon the top of the shelf 6, the outer end of said arm being bent upwardly and rigidly connected to a projection 21 on a closure body 8 having a smooth flat lower 65 surface.

Referring to said Fig. 3, the numeral 11 denotes a threaded depending stud on the under face of the shelf 6. A plate 16 has a flat top placed in contact with the under 70 face of the shelf 6 and is apertured to be seated rockingly upon said stud 11. A rod spring 13 has one end passed through a transverse hole 14 in the stud 11 contactingly with the under face of the plate 16, 75 and is curved around the stud with its outwardly projecting part bent upwardly terminally and seated in a hole in an ear 15 on an annular body 17 which is rigidly mounted around the open top of one end of 80 an U-shaped tube 18. A nut 12 on the threaded termination of the stud 11 is in contact with the inner part of said spring. The body 17 is a part of and depending 85 from the plate 16 and the plate has a common aperture with said body 17 and said tube.

The outer part of the tube 18 is somewhat longer vertically than the inner member thereof, but may be otherwise, and has an 90 annular delivery tip 19 mounted removably on a threaded termination 23 thereof. The tip 19 as shown, however, is closed and its closed top has a plurality of small delivery apertures 10 to deliver water therethrough 95 to a drinker. The tip may be merely an open annulus to deliver an unbroken stream therethrough. The set-screws 5 serve conveniently to secure the sleeve upon the termination of the faucet spout 3, and in such 100 a manner that the sleeve may be fitted removably upon any spout however short. The tube 18 has a minute drain hole 25 therein.

The spring 13 normally keeps the tube 18 105 swung around to a position where its delivery tip 19 is under and closed by the flat imperforate under face of the closure body 8 and is stopped thereby by the depending stop projection 9. At the same time the 110 open end of the other member of the tube 19 is closed by the flat under face of the shelf

6, as shown in said Fig. 1. The body 8 may have an edge truncated at 10 to permit the tip 19 to pass thereunder without clashing.

The device may be used by manually 5 swinging the tube 18 around until the edge of the plate 16 contacts with the stop 20, at which time the tube communicates with the sleeve 4 and spout 3. The operator may then rock the faucet handle 2 far enough 10 to permit a sufficient supply of water to flow through the tube 18 and the delivery openings 23 of its tip. When the tube 18 is released by the drinker, the spring 13 reacts to swing back the tube to close its open 15 ends as hereinbefore described. The tube cannot be left carelessly open when not in use, consequently, as its ends are closed so that no foreign matter can enter them, so that the interior of the tube is kept in a 20 sanitary condition. The tip may be removed for cleaning.

It will be understood that when the drinker initially rocks the tube 18 to its 25 delivery position, the spring 13 is placed under tension, and when released the spring is strong enough to return the tube to its said closed position.

Having described my invention, what I 30 claim as new, and desire to secure by Letters Patent, is:

1. In combination, an open end delivery tube, means for removably mounting it 35 rockingly upon and to communicate at times with the open end of a spout, and closure means mounted upon said mounting means, whereby the tube may be rocked out of communication with said spout and in a position where its open ends are closed by said closure means.

40 2. In combination, an open end delivery tube, means for removably mounting it rock- 45 ily upon and to communicate at times with the open end of a spout, and closure means positioned so that when it is rocked out of communication with the spout its open ends are closed by the closure means.

3. In combination, an open end delivery tube, means for removably mounting it 50 rockingly upon and to communicate at times

with the open end of a spout, resilient means 55 operative upon said tube to normally rock it out of communication with the spout, and closure means positioned so that when it is rocked out of communication with the spout its open ends are closed by the closure means. 55

4. In combination, an open end delivery tube, means for mounting it rockingly upon and to communicate at times with the open end of a spout or conduit, closure means positioned so that when said tube is rocked 60 out of communication with the spout or conduit its open ends may be closed by the closure means, and stops upon said mounting and said closure means adapted to limit the scope of movement of the tube in oppo- 65 site directions.

5. In combination, an U-shaped delivery tube, means for mounting it rockingly upon a termination of a conduit to communicate at times therewith, and means for closing 70 the open ends of said tube when rocked out of communication with the conduit.

6. In combination, an U-shaped delivery tube having an apertured closed delivery 75 termination and a drainage hole at its lowest point, said tube having its other termination rockingly mounted upon an open end of a conduit for occasional communication therewith, and means for closing both ends of 80 said tube when out of communication with the conduit.

7. In combination, a delivery tube mounted rockingly upon and to communicate occasionally with a conduit, closure means also mounted on said conduit and spaced apart 85 whereby when the tube is rocked in one direction to place it out of communication with said conduit both its ends will be closed by said spaced closure means, resilient means also mounted on said conduit bearing upon said tube to normally rock it to a position to cause said closure means to close the ends of the tube, and means for restricting the scope of rocking movement of 90 the tube. 95

In testimony whereof I affix my signature.

LOUIS C. RATHBUN.
